UNITED STATES PATENT OFFICE.

ALFRED COTTON, OF NEWARK, NEW JERSEY.

FURNACE-GRADE.

No. 823,715.

Specification of Letters Patent.

Patented June 19, 1906.

Application filed September 21, 1905. Serial No. 279,396.

To all whom it may concern:

Be it known that I, ALFRED COTTON, a subject of the King of Great Britain, residing at Newark, in the county of Essex and State of New Jersey, have invented certain new and useful Improvements in Furnace-Grates, of which the following is a specification, reference being had therein to the accompanying drawings, in which—

- 10 Figure 1 is a longitudinal sectional view showing my improved grate in position under a boiler; Fig. 2, a plan view of a portion of the grate; Fig. 3, a transverse vertical sectional view of several grate-bars interlocked, taken approximately on the line III III of Fig. 6, spacing-washers being inserted between the grate-bars; Fig. 4, a side elevation of one grate-bar; Fig. 5, a horizontal sectional view on the line V V of Fig. 4; Fig. 6, a 15 detail plan view of a portion of the grate, and Fig. 7 a detail transverse sectional view taken on the line VII VII of Fig. 6.
- 20

This invention relates to that class of fire-grates which are adapted for use with all solid fuels, but which are more particularly adapted for use with small or powdery coal or coke breeze and house refuse, in conjunction with forced draft.

One of the many objects of this invention 25 is to provide a grate made up of a series of small grate-bars which are loosely interlocked in such manner that no one grate-bar or set of grate-bars can be lifted independently of the other grate-bars.

30 Many other important objects of the invention will appear hereinafter.

Referring to the various parts by reference characters, 1 designates the front bearer or support, 2 the rear bearer, and 3^a the intermediate bearers. These bearers extend transversely of the ash-pit, and the intermediate bearers are double—that is, they are formed of two parallel transverse bars arranged comparatively close together, so as to support the adjoining ends of the grate-bars—as will be 45 more fully hereinafter described.

As shown in the drawings, the grate consists of three transverse ranks of grate-bars A, B, and C, which are arranged in files, so 50 that three bars are end to end in each file. The end ranks are each composed of long and short bars 3 and 4, respectively, arranged alternately side by side. The forward ends of the bars in the front rank are arranged on the same transverse line, so that the rear ends of said bars terminate on different lines—

that is, the rear ends of the long bars project rearward beyond the ends of the short bars. The rear rank of bars is composed also of long and short bars, and the rear ends of these 60 bars are arranged on the same line, so that the forward ends of the bars of this rear rank terminate on different lines. The forward ends of the longer bars therefore extend beyond the ends of the shorter bars. The short bars 65 of the rear rank are arranged in the same longitudinal lines as the long bars of the front rank. The intermediate bars 5 are all of the same length. One longitudinal line or file of bars will consist of one long bar in the 70 front rank, one intermediate bar, and one short bar in the rear rank, the adjoining line or lines or file or files of bars consisting of a short bar in the front rank, an intermediate bar, and a long bar in the rear rank, as shown 75 clearly in Fig. 2 of the drawings. By this arrangement of the bars there is no continuous transverse line of division between the ranks of the bars, the bars in alternate files breaking joints. 80

In many of the grates heretofore constructed of a series of ranks of bars a continuous transverse space was formed between the adjoining ends of the bars of the ranks. This transverse space is very objectionable in that 85 the small fuel drops through it and the firing-tools frequently are caught in it. A further objection is that these continuous transverse spaces will permit a large quantity of air to pass upward, thereby preventing an even 90 distribution of the draft throughout the grate.

Each bar is provided near each of its ends with two laterally-extending horizontal bosses 6 and 6^a on one of its sides and with an 95 outward-extending horizontal flange 7 on its other side, the upper surface of said flange being flush with the upper surface of the grate-bar, as shown clearly in Figs. 3 and 7. At a point in the same transverse plane with 100 each of the end bosses 6 and slightly below them and on the opposite side of the grate-bar are formed the horizontal ribs 8, said ribs being spaced below the flange 7 a distance slightly larger than the vertical diameter of 105 the bosses 6, as shown clearly in Fig. 7. Each bar is also formed with horizontal lugs 9 on the opposite side of the bar from the bosses 6^a and at a distance below the flange 7 slightly larger than the vertical diameter of 110 the bosses 6^a, the lugs 9 being in the same transverse plane with the bosses 6^a and in the

same horizontal plane with the end ribs 8. The flange 7 directly above the lugs 9 is formed with lateral horizontal enlargements 10. The said flange at its ends is formed 5 with the lateral enlargements 11, which are connected to the outer ends of the ribs 8, and thereby close the outer ends of the cavities formed between the flange 7 and the said ribs. The enlargements 10 and 11, the rib 8, 10 and the lug 9 all terminate in the same longitudinal vertical plane, as shown clearly in Figs. 3 and 7. Each bar is formed with a vertical rib 12 midway between its ends, said rib extending from the top of the flange 7 to 15 the base of the bar, its outer face being in the same longitudinal vertical plane as the ends of the lugs 9 and ribs 8, as shown clearly in Fig. 5 of the drawings.

In assembling the bars the boss 6^a of one 20 long bar 3 of the end rank will enter the cavity or space between the rib 8 and flange 7 at the enlargement 11 of one adjoining short bar 4 of the same rank, and the boss 6 will enter the space between the rib 8 and the 25 flange 7 at the enlargement 11 of one of the adjoining bars 5 of the intermediate rank, as shown very clearly in Fig. 6. The bosses 6 of the short bars 4 of the end rank extend under the flange 7 just below the enlargements 10 and above the lugs 9 of the adjoining long bars 3, as shown in Fig. 6, while the 30 bosses 6^a extend under the flange 7 of said adjoining long bar 3. The bosses 6 on alternate bars 5 of the intermediate rank extend 35 between the ribs 8 and the flanges 7 directly below the enlargements 11 of the long bars 3 of the end rank, the bosses 6^a of said intermediate bars extending into the adjoining intermediate bars directly below the enlargements 11 and above the ribs 8. The bosses 6^a of the intervening bars of the intermediate 40 or middle rank extend below the flange 7 of the adjoining intermediate bars, the end boss 6 of each of said bars fitting between the enlargements 10 and the lug 9 on the adjoining bar 5. By this arrangement it will be noted 45 that the long bars of the end ranks are each locked to the adjoining short bars of the same rank and to one bar of the intermediate or 50 middle rank. The next adjoining short bars of the end ranks are locked, by means of their bosses 6 and 6^a, to the adjoining longer bars of the end ranks. Alternate bars of the 55 intermediate or middle rank are locked to the long bars of the end ranks, the front ends of one set of bars being locked to the long bars of the first or front rank, the other ends of said bars being locked to adjoining bars of the intermediate or middle rank, and the intervening bars of the middle rank are locked 60 at their rear ends to the long bars of the rear rank, the other ends of said bars being locked to the adjoining bars which are in turn secured at their forward ends to the front rank. 65 From this arrangement it will be noted that

the entire grate is loosely interlocked and that no bar can be vertically moved (except to a very slight extent by reason of the play between the bosses and the confining ribs and lugs) independent of the other bars of 70 the grate. It will also be noted that the bars individually or in ranks or files will be incapable of endwise movement on the bearers, except, of course, through the spaces which must necessarily be left between the bars to 75 admit of expansion and contraction.

The enlargements 10 and 11 and ribs 12 of one bar bear against the face of the adjoining bar to provide the longitudinal air-spaces between the bars. 80

Whenever it may be desired to form large air-spaces between the bars, washers 13 may be placed over the bosses 6 and in position to rest against the adjoining lugs 9 and enlargements 10, as shown in Fig. 3, in order 85 to space the bars apart transversely.

It will of course be understood that the cavities in the sides of the grate-bars to receive the bosses of the adjoining bars may be made in any suitable manner and of any 90 suitable shape. The method of forming these cavities described herein I considered a good method to be followed in practice, as it is practicable to cast the bars in the form shown. It will also be understood that 95 some of the bars need only one boss at one of their ends; but I prefer to cast the bars with two bosses at each end in order to simplify the process of manufacture, as fewer molds and patterns need be used. The 100 bosses 6 and 6^a form means for interlocking the adjoining ends of the bars, and, as shown, these interlocking means are integral with the grate-bars.

Having thus described my invention, what 105 I claim as new, and desire to secure by Letters Patent, is—

1. A grate consisting of a plurality of files each file being formed of a series of grate-bars arranged end to end in such manner as 110 to break joints with bars in adjoining files, and means for interlocking the overlapped ends of said grate-bars against independent vertical movement.

2. A grate formed of a series of grate-bars 115 arranged in longitudinal files or lines and in transverse ranks, the bars in one file breaking joints with the bars in adjoining files, means for loosely interlocking the overlapped ends of adjoining bars, and means 120 for loosely interlocking against independent vertical movement the outer ends of the bars of the end ranks.

3. A grate composed of a series of grate-bars arranged in longitudinal files or lines 125 and transverse ranks or groups, the bars of the intermediate rank or ranks overlapping some of the bars of the end ranks and means for interlocking the overlapped ends of the bars of one rank with the bars of the adjoin- 130

ing rank and for interlocking the bars of the end ranks which are not overlapped with those that are overlapped.

4. A furnace-grate composed of a series of grate-bars arranged in ranks and files, means formed integral with each bar for loosely interlocking it with the adjoining bars of the same rank against vertical and endwise movement and for interlocking some of the bars of one rank with the adjoining bars of the next rank, whereby the ranks will be interlocked against independent endwise or vertical movement.

5. A furnace-grate composed of a series of grate-bars arranged in ranks and files the end ranks being formed of long and short bars, the long bars extending inward beyond the ends of the short bars, and an intermediate or middle rank composed of bars of equal length, means on the long bars of the end ranks for loosely interlocking said bars with the adjoining bars of the intermediate rank and means on the adjoining short bars of the end ranks, and the bars of the intermediate rank to loosely interlock said bars with the long bars of the end ranks and the adjoining bars of said intermediate rank.

6. A grate formed of a series of bars arranged in files and ranks, the bars in the files being arranged end to end and the bars in the ranks being so arranged that the bars of one file will break joints with the bars in the adjoining files, means for interlocking the ends of said bars against independent vertical movement.

7. A grate formed of a series of bars arranged in files and ranks, the bars in the files being arranged end to end and the bars in the ranks being so arranged that the bars of one

file will break joints with the bars in the adjoining files, means integral with the bars and projecting from the sides thereof to interlock said bars against independent vertical movement.

8. A grate formed of a series of bars arranged in files and ranks, the bars in the files being arranged end to end and the bars in the ranks being so arranged that the bars of one file will break joints with the bars in the adjoining files, and means for interlocking the bar which breaks the joints between the bars of adjoining files to the four adjoining bars.

9. A grate formed of a series of bars arranged in files and ranks, the bars in the files being arranged end to end and the bars in the ranks being so arranged that the bars of one file will break joints with the bars in the adjoining files, each bar being provided on one side and near each of its ends with a pair of horizontal laterally-extending bosses 6 and 6^a and on its other side near each of its ends with the rib 8 and an enlargement 11 and with the rib 9 and an enlargement 10, the rib 8 and enlargement 11 being in the same transverse plane with the bosses 6 and the rib 9 and the enlargements 10 being in the same transverse plane with the bosses 6^a, said ribs and enlargements being separated from each other vertically a distance substantially equal to the diameter of the joining boss 6 or 6^a.

In testimony whereof I hereunto affix my signature, in the presence of two witnesses, this 17th day of June, 1905.

ALFRED COTTON.
